UNITED STATES PATENT OFFICE.

CHARLES SPIRO, OF NEW YORK, N. Y.

STENOGRAPHIC TYPE-WRITER.

1,160,665.

Specification of Letters Patent. Patented Nov. 16, 1915.

Application filed December 21, 1914. Serial No. 878,288.

To all whom it may concern:

Be it known that I, CHARLES SPIRO, a citizen of the United States, residing at New York, in the county of New York and State of New York, have invented certain new and useful Improvements in Stenographic Type-Writers, of which the following is a specification.

This invention relates to a stenographic typewriter and particularly to a construction wherein a series of typebars are adapted to print either singly or a plurality thereof simultaneously to produce a proper stenographic symbol upon an automatically fed strip passing over a platen.

The invention has for an object to provide a platen having a plurality of independent tracks or fields, only one thereof being normally in printing relation to the typebars, and another adapted to be shifted into such relation when the first mentioned field is removed therefrom.

Another object of the invention is to provide such a platen mounted in a carriage for lateral movement and adapted to be automatically fed in a rotary direction after each depression of a typebar.

Other and further objects and advantages of the invention will be hereinafter set forth and the novel features thereof set forth by the appended claims.

In the drawing—Figure 1 is a vertical section on the line 1—1 of Fig. 2; Fig. 2 is a top plan; Fig. 3 is a detail of a printed strip, and Fig. 4 is a detail of a modified form of the invention.

Like numerals of reference refer to like parts in the several figures of the drawing.

The numeral 10 designates the frame of the typewriter which may be of any desired construction or configuration suitable for the purpose. Within this frame a series of integral typebars and key levers 11 are mounted upon a common pivot or fulcrum 12 and adapted to engage a platen 13. These typebars are provided with the usual keys 14 and may carry any desired characters for the work to be accomplished. A space key 15 is also mounted upon the pivot 12 to operate in the ordinary manner. This key and also the key levers are disposed above a universal bail or bar 16 which is formed at each end with lateral arms 17 mounted upon the pivot 12. The bail and levers engaging the same are normally held in raised position by a spring 18 arranged

upon at least one arm. The levers 11 form a key lever at one end and a type bar at the other.

The platen 13 is pivotally mounted at 19 in a carriage 20 slidably supported upon the cross rods 21 carried by the frame 10. In the present instance no mechanism is shown for accomplishing the sliding movement of the carriage, the same being most simply effected by hand. The carriage is formed with a rearward extension or bracket 22 adapted to removably support a rolled sheet or strip of paper as shown at 23. This strip is fed over a tension roll 24 yieldingly mounted on the carriage and held in contact with the platen by a spring 25. The strip extends over a portion of the periphery of the platen and beneath a binding rod 26 mounted in a forward extension 27 of the carriage.

The typebars are arranged with their printing characters in a line extending across a portion of the platen, indicated as the normal printing track or field 30, so as to print either one or a plurality of characters simultaneously by a single action of the fingers upon the keys. At one side of this normal track 30 is an auxiliary track or field 31, ordinarily not used in writing, but adapted to be moved into alignment with the typebars as the normal field is moved out of such position. This provides a field on which corrections, interpolations, or other desired memorandum may be noted immediately adjacent the original text, instead of on a separate sheet as usual. A proper indicator 32 may be located upon the binding rod 26 to determine the extent of each of these fields.

The platen is provided with an automatic rotary step-by-step feed, preferably by a pawl 33 carried by the arms 17 of the universal bail. This feed may be effected by other means, but in the present illustration the pawl 33 extends across the front of the platen and for a greater length so as to be constantly in engagement with a ratchet 34 secured to the platen and of greater diameter than the latter. This pawl is substantially U-shaped and the depending arms 35 thereof are pivoted at 36 to the arms 17 of the bail. The pawl is held in constant engagement with the ratchet by means of a spring 37 extending between the arms 35 and 17. This causes the pawl to be depressed at each downward movement of a

type or space lever and in the restoring action of such lever the platen is fed forward one step so that the printed characters are arranged in parallel horizontal lines at one 5 side of the strip when two fields are used as shown in Fig. 3. Under some conditions it may be desirable to use more than two fields, and the modified form of the invention shown in Fig. 4 illustrates a platen 38 having 10 three fields, the normal printing field 39 being at the center and the auxiliary fields 40 at opposite sides thereof.

No inking ribbon mechanism is herein shown but any desired form may be used. 15 It has ordinarily been found sufficient to use a soft platen with a thin paper sheet or strip and a carbon paper or cloth backing having its coated face next the paper as indicated in Fig. 3. The impression from the 20 raised type takes up sufficient carbon to make the character clearly visible through the thin paper.

In stenographic typewriters now in use when interpolations or memorandum relating 25 to the original text are made they must be placed upon a separate sheet or at a place upon the printed sheet removed from their application to said text and reference thereto made. This invention provides a normal 30 writing field to receive the original text and a parallel auxiliary field adapted to be shifted immediately into alinement with the type-bars at their printing point to receive notation of any changes or interpolations directly 35 adjacent the portion of the original text to which they relate. After such notation the platen may be at once shifted back to the normal field and the original text thereon continued. In this construction of 40 machine either one key may be depressed to print or a plurality thereof simultaneously to produce a word symbol at a single stroke and after each stroke the paper is automatically fed forward one space so that the 45 characters are printed in parallel horizontal lines adjacent a blank or auxiliary field for the purposes set forth. The feed pawl is constantly in engagement with the platen ratchet so that the latter may be shifted to 50 any position and still be automatically fed.

A number of details of construction have been shown and described but the invention is not specifically confined thereto but relates primarily to the structure embodying 55 the use of the normal and auxiliary fields or tracks as defined by the appended claims.

What I claim is:—

1. In a stenographic typewriter, type bars adapted to simultaneously print a plurality 60 of characters in a predetermined field, and a platen bodily shiftable alongside said field and adapted to have independent or distinct portions thereof brought over said type bars thereby providing independent 65 fields for writing, one of which is adapted

to receive the complete main text to be written and the other notations in alinement with and referring to said text.

2. In a stenographic typewriter, type bars adapted to print a plurality of characters in a predetermined field, and a platen bodily shiftable alongside said field and adapted to have independent or distinct portions thereof brought over said type bars thereby providing independent fields for writing 70 at a right angle to the normal automatic platen feed, one of which is adapted to receive the complete main text to be written and the other notations in alinement with and referring to said text.

3. In a stenographic typewriter, type bars adapted to simultaneously print a plurality of characters in a predetermined field, and a platen rotatable in the ordinary composition and bodily shiftable longitudinally 75 alongside said field and adapted to have independent or distinct portions thereof brought over said type bars thereby providing independent fields for writing, one of which is adapted to receive the complete 80 main text to be written and the other notations in alinement with and referring to said text.

4. In a stenographic typewriter, type bars adapted to simultaneously print a plurality 95 of characters in a predetermined field, and a platen bodily shiftable alongside said field and having an automatic rotary feed and adapted to have independent or distinct portions thereof brought over said type bars thereby providing independent fields for writing, one of which is adapted to receive the complete main text to be written and the other notations in alinement with and referring to said text.

5. In a stenographic typewriter, type bars adapted to simultaneously print a plurality of characters in a predetermined field, and a normally longitudinally stationary platen bodily shiftable alongside said field and having an automatic rotary feed and adapted to have independent or distinct portions thereof brought over said type bars thereby providing independent fields for writing, one of which is adapted to receive the complete main text to be written and the other notations in alinement with and referring to said text.

6. In a stenographic typewriter, type bars adapted to simultaneously print a plurality 110 of characters in a predetermined field, a platen bodily shiftable alongside said field and adapted to have independent or distinct portions thereof brought over said type bars thereby providing independent fields 115 for writing, each covering the printing area, of all of the type bars, and means to permit the selective shifting of said platen to bring either field into printing position.

7. In a stenographic typewriter, type bars 120

adapted to simultaneously print a plurality of characters in a predetermined field, a platen bodily shiftable alongside said field and adapted to have independent or distinct 5 portions thereof brought over said type bars thereby providing independent fields for writing, each covering the printing area of all of the type bars, means to permit the selective longitudinal shifting of said platen 10 to bring either field into printing position, and means controlled by said type bars for automatically rotating said platen when in either of said fields.

8. In a stenographic typewriter, type bars 15 adapted to simultaneously print a plurality of characters in a predetermined field, a platen bodily shiftable alongside said field and adapted to have independent or distinct portions thereof brought over said type 20 bars thereby providing independent fields for writing, and a pawl fixed relative to the longitudinal travel of the platen and extending longitudinally across the same to impart a step-by-step rotary feed thereto when 25 either of said fields is in printing position.

9. In a stenographic typewriter, type bars adapted to simultaneously print a plurality of characters in a predetermined field, a platen bodily shiftable alongside said field 30 and adapted to have independent or distinct portions thereof brought over said type bars thereby providing independent fields for writing, a pawl fixed relative to the longitudinal travel of the platen and 35 extending longitudinally across the same to impart a step-by-step rotary feed thereto when either of said fields is in printing position, and means actuated by said type bars for automatically operating said pawl.

10. In a stenographic typewriter, type 40 bars, a platen having a plurality of fields and mounted for longitudinal movement to shift either of said fields into alinement with said typebars, a universal bail disposed 45 beneath and actuated by said type bars, and a pawl carried by said bail and extending

longitudinally across said platen to impart a rotary step feed to said platen when either field is in printing position.

11. In a stenographic typewriter, a series 50 of type bars pivoted upon a common fulcrum, a universal bail disposed beneath and actuated by said type bars, a sliding carriage, a platen pivoted therein and having a plurality of fields one of which is normally 55 in printing relation to said type bars, a feed ratchet upon said platen, and a feed pawl pivoted on said universal bail and engaging said ratchet to effect a rotary movement of said platen. 60

12. In a stenographic typewriter, a series of type bars pivoted upon a common fulcrum, a universal bail pivoted on said fulcrum and disposed beneath and actuated by said type bars, a sliding carriage, a platen 65 pivoted therein provided with a ratchet and having a plurality of fields one of which is normally in printing relation to said type bars, and a U-shaped feed pawl extending longitudinally of the platen and pivoted at 70 each end to said universal bail to coöperate with said ratchet and produce a rotary platen feed. 70

13. In a stenographic typewriter, type 75 bars, a universal bail disposed beneath said type bars, a sliding carriage provided with a roll supporting bracket at its rear, a platen pivoted in said carriage and having a plurality of fields one of which is normally in printing relation to said type bars, a yielding tension roll engaging said platen to control the paper feed thereon, a feed ratchet carried by said platen, and a pawl 80 engaging said ratchet and actuated by said universal bail to effect a rotary movement 85 of said platen.

In testimony whereof I affix my signature in presence of two witnesses.

CHARLES SPIRO.
